US00D931880S

(12) **United States Design Patent** (10) Patent No.: **US D931,880 S**
McDonald et al. (45) Date of Patent: ** *Sep. 28, 2021

(54) DISPLAY SCREEN OR PORTION THEREOF WITH GRAPHICAL USER INTERFACE	29/00; B60H 1/00; B60H 1/32; G05D 23/00; B60Q 1/26; H04L 51/04
(71) Applicant: Carrier Corporation , Palm Beach Gardens, FL (US)	See application file for complete search history.
(72) Inventors: Patrick McDonald , Athens, GA (US); John F. Hannon , Pennellville, NY (US); Mark Fragnito , Watkinsville, GA (US); Deborah A. Champagne , Syracuse, NY (US); Thaison Phan , Syracuse, NY (US); Ken Shuart , Danielsville, GA (US); Vohn McLeish , Athens, GA (US)	
(73) Assignee: CARRIER CORPORATION , Palm Beach Gardens, FL (US)	
(*) Notice: This patent is subject to a terminal disclaimer.	
(**) Term: 15 Years	
(21) Appl. No.: 29/726,553	
(22) Filed: Mar. 4, 2020	
Related U.S. Application Data	
(63) Continuation of application No. 29/701,185, filed on Aug. 8, 2019.

CLAIM

We claim, the ornamental design for a display screen or portion thereof with graphical user interface, as shown and described.

DESCRIPTION

The FIGURE is a front view of a display screen or portion thereof with graphical user interface, showing our new design.

The broken lines in the figure represent no part of the claimed design. The solid black shading represents contrast in appearance with other adjacent portions of the claimed design.
